(57) **CLAIM**

The ornamental design for a hook end gripper of load securing straps, as shown and described.

DESCRIPTION

FIG. 1 is a front top, exploded, perspective view of the hook end gripper of load securing straps;

FIG. 2 is a rear top, exploded perspective view thereof;

FIG. 3 a front top perspective view;

FIG. 4 a rear top perspective view;

FIG. 5 a front plan view;

FIG. 6 a right side elevation view, the left side elevation view being a mirror image thereof;

FIG. 7 a top plan view;

FIG. 8 a bottom plan view; and,

FIG. 9 a rear plan view.

1 Claim, 4 Drawing SheetsFIG. 1

FIG. 2

FIG. 3

FIG. 4

FIG. 7

FIG. 5

FIG. 6

FIG. 8

FIG. 9
